(57) **CLAIM**

The ornamental design for a dump truck body, as shown and described.

DESCRIPTION

FIG. 1 is a perspective view of a first embodiment of a dump truck body of our design;

FIG. 2 is a top view of the first embodiment of the dump truck;

FIG. 3 is a right side view of the first embodiment of the dump truck body, the left side being a mirror image thereof;

FIG. 4 is a back view of the first embodiment of the dump truck body;

FIG. 5 is a front view of the first embodiment of the dump truck body;

FIG. 6 is a bottom view of the first embodiment of the dump truck body;

FIG. 7 is a perspective view of a second embodiment of a dump truck body of our design;

FIG. 8 is a top view of the second embodiment of the dump truck body;

FIG. 9 is a right side view of the second embodiment of the dump truck body, the left side being a mirror image thereof;

FIG. 10 is a back view of the second embodiment of the dump truck body;

FIG. 11 is a front view of the second embodiment of the dump truck body; and,

FIG. 12 is a bottom view of the second embodiment of the dump truck body.

The broken line showing of environment is for illustrative purposes only and forms no part of the claimed design.
